CARPENTER'S HORSE

William J. McDonald, Kansas City, Mo.

Application November 14, 1938, Serial No. 240,365

5 Claims. (Cl. 304—5)

My invention relates to carpenter's horses, and more particularly a carpenter's horse that is made up of metal frame members and lumber ordinarily found on a building job.

It is a purpose of my invention to provide a carpenter's horse that is made up of a pair of duplicate frame members, that is simple and cheap in construction, and which at the same time will make a strong and rigid horse when the frame members are assembled with pieces of lumber ordinarily plentiful on a building job.

It is a further purpose of my invention to provide a carpenter's horse of the above mentioned character, which is capable of quick assembly and the metal portions of which can be readily transported from place to place.

It is still a further purpose of my invention to provide a carpenter's horse of the above mentioned character, which is provided with means for providing a longitudinal member below the top member thereof, which serves as a shelf for tools and other equipment, and also acts as means for bracing the horse.

Previously, my improved carpenter's horse is made up of frame members comprising leg portions and a transverse portion to which the top piece, or pieces, of the horse are secured, which leg portions and transverse portions are integral with each other, and to provide shelf supporting means bracing said leg portions and extending between the same, said leg portions being, preferably, channel-shaped with the flanges thereof turned outward to permit of the more ready securing of the shelf supporting bracing portion thereto in fixed position.

Other objects and advantages of my invention will appear as the description of the drawing proceeds. I desire to have it understood, however, that I do not intend to limit myself to the particular details shown or described, except as defined in the claims.

In the drawing:

Fig. 1 is a longitudinal vertical sectional view through my improved carpenter's horse, taken substantially on the line 1—1 of Fig. 2.

Fig. 2 is an end view of my improved horse, and

Fig. 3 is a fragmentary view in perspective of the upper portion of one of the frame members forming the legs and supporting means for the top and shelf portions.

Referring in detail to the drawing, my improved carpenter's horse is made up of frames that are made of metal and are, preferably, made principally of a piece of channel iron, although the same can be made of a piece of flat heavy

sheet metal, only portions of which are flanged, as will be explained in connection with the description of said frame members.

Said frame members have leg portions 5 which are channel-shaped in cross section, having the outwardly directed flanges 6 thereon. Said leg portions diverge from each other transversely of the horse and are inclined at an angle to the transverse connecting portion 7, so that the leg portions of the two frames extend away from each other when assembled in the horse, as shown in Fig. 1, this being accomplished by bending the piece of material from which the transverse portion 7 and the leg portions 5 are made obliquely at the points indicated by the numeral 8 in Fig. 3. The flat, or plane, connecting portion 7 thus tapers so that the legs 5 are closer together at the portion thereof that is rearmost as shown in Fig. 3. If the legs 5 and transverse portions 7 are made of a piece of channel iron, the flanges 6 of the channel are bent outwardly so as to extend the same in the same plane as the web portion of the channel, to provide the flat transverse top member 7. In order that the flanges 6 do not extend upwardly above the plane of the top face of the member 7, it is necessary to cut these off at an oblique angle, so that when the member is made out of channel iron it must be notched on opposite sides of the portion that is to form the flat top member 7, so as to permit bending of the same into the shape shown, and to prevent the flanges 6 from extending upwardly above the top face of the member 7, said notches being V-shaped, as will be obvious.

The transverse portion 7 is thus considerably wider than the leg portions 5, providing a smooth flat face for engagement of the member 9, made of wood, which is secured thereto, to form the top part of the horse, by means of the countersunk headed securing elements 10, such as bolts, which extend through openings bored in the piece of lumber 9 and through openings 11 provided in the flat transverse top portion 7 of each frame. The holes 11, it will be noted, are staggered so that the hole 11 on one side of the member 7 is out of line with the two holes 11 on the other side thereof. The top member 9 is, preferably, made of a length such that it will extend considerably beyond the flat portions 7 of the frame members, as will be obvious from Fig. 1.

A transversely extending angle member 12 is provided, connecting the inclined leg portions 5, said angle member having an upstanding flange 13, against which the end of the wooden shelf

member 14, made of a suitable piece of lumber, abuts to prevent any endwise shifting of said member 14 relative to the angle members 12, said angle members 12 being provided with openings 15 for the bolts 16 for securing the piece of lumber 14, forming the shelf, to said angle members, said holes being, preferably, staggered.

The angle member 12 is provided with depending ear portions 17, which are formed by cutting off the flange 13 from the angle member 12 at the ends thereof and bending down the ears 17 at an oblique angle, said ears 17 being, of course, extended in a plane that is both oblique to the flange 13 and the bottom flange of the angle member 12, to thus cause said ears 17 to lie flatwise against the obliquely inclined inner faces of the web portions of the channel-shaped legs 5. Said ears 17 are secured rigidly in fixed position on the inner faces of the leg portions 5, by riveting, or welding, or in any other manner, rivets 13 being illustrated as being provided for this purpose. Openings 18 are also provided in the legs 5 above the angle members 12, so that bracing members 20 can be pivoted to the leg portions 5, by means of bolts 21, should this be desired or found necessary, said bracing members being provided with eyes 22 for pivotally mounting the same on the bolts 21, and being provided with eyes 23 that lie in a plane transverse to that of the eyes 22 for securement flatwise to the under side of the top forming member 9, by means of bolts 24, which are countersunk, as will be evident, one bolt 24 being provided for each pair of members 20, the same inclining toward the center line of the horse, as will be evident from Fig. 2.

It will be obvious that the frame members, instead of being made out of structural shapes and cut and bent into such shape as shown in the drawing, can be made of sheet metal, cut and flanged as shown, provided a sufficiently heavy gauge of sheet metal is used to obtain the desired strength and rigidity for the frame members.

45. What I claim is:

1. In a device of the character described, a rigid, integral frame member comprising a flat transverse top portion and legs channel-shaped in cross section integral with said top portion diverging from each other downwardly from said top portion and extending obliquely to a transverse plane perpendicular to said top portion, and a bracing member angular in cross section extending between said legs in spaced relation to said top portion, said bracing member having a horizontal leg and an upwardly directed flange and having depending integral ears extending at an oblique angle to said horizontal leg and rigidly secured to said diverging legs.

60. 2. In a device of the character described, a rigid frame member comprising a flat transverse top portion and legs channel-shaped in cross section integral with said top portion diverging from each other downwardly from said top portion, said frame members being bent on divergent lines at the junction of said top portion and said legs so that said legs extend at an oblique angle to a transverse plane perpendicular to said top

portion, the flanges on said leg portions being directed outwardly, and a bracing member angular in cross section connecting said legs in spaced relation to said top portion, said bracing member having an upwardly directed flange and having downwardly obliquely extending integral ears secured to the flat inner faces of said legs.

3. In a device of the character described, a rigid frame member comprising a flat transverse top portion and legs channel-shaped in cross section integral with said top portion, said legs diverging from each other downwardly from said top portion and also both extending obliquely relative to said top portion in the same direction to bias said top portion relative to said legs, a bracing member angular in cross section connecting said legs in spaced relation to said top portion, said bracing member having an upwardly directed flange and having obliquely extending integral ears secured to said legs, and a second set of bracing members each pivotally mounted on the inner faces of one of said leg portions and converging from said pivotal mounting.

4. A carpenter's horse comprising a pair of metallic frame members, each comprising a flat transverse top portion and legs channel-shaped in cross section integral with said top portion diverging from each other downwardly from said top portion, said top portion and said leg portions being joined on lines oblique to each other, a longitudinal top member overlying and bolted on said top portions of said frames face to face so that said legs diverge downwardly both lengthwise and crosswise of said horse, each frame having a bracing member angular in cross section connecting said legs in spaced relation to said top portion, said bracing member having an upwardly directed flange and having obliquely extending integral ears secured to said legs, and a longitudinal bracing member forming a shelf secured to said angular bracing members with the ends thereof in engagement with said upstanding flanges thereof.

5. A carpenter's horse comprising a pair of metallic frame members, each comprising a flat transverse top portion and legs channel shaped in cross section integral with said top portion diverging from each other downwardly from said top portion and extending obliquely to the central plane of said top portion, the flanges on said leg portions being directed outwardly, a longitudinal top member overlying and bolted on said top portions of said frames with said legs diverging downwardly both lengthwise and crosswise of said horse, each frame having a bracing member angular in cross section connecting said legs in spaced relation to said top portion, said bracing member having an upwardly directed flange and having downwardly obliquely extending integral ears secured to the inner faces of said legs, a longitudinal bracing member forming a shelf secured to said angular bracing members with the ends thereof in engagement with said upstanding flanges thereof.

WILLIAM J. McDONALD.
